COKE TREE PREVENTING GUARD FOR BOILERS AND FURNACES

Santo Imbresci, Chicago, Ill.

Application February 10, 1948, Serial No. 7,363.

6 Claims. (Cl. 110—45)

This invention relates to improvements in coke trees preventing guards for boilers and furnaces.

An object of the invention is to provide an improved fire guard for positioning upon the top of the fire bed in any stoker fired boiler or furnace to automatically prevent the building up or formation of coke trees in the boiler or furnace.

Another object of the invention is to provide an improved form of fire guard which will be supported upon the fire bed in any stoker fired boiler or furnace to prevent the building up or formation of coke trees in the boiler or furnace, and said guard having means associated therewith whereby the same may be raised when clinkers are being removed from the boiler or furnace.

A further object of the invention is to provide an improved coke tree preventing guard for boilers and furnaces which will be highly efficient in operation and relatively inexpensive to manufacture and produce.

Other objects will appear as the description proceeds.

In the accompanying drawings, which form a part of this application,

Figure 1 is a side elevation of a boiler or furnace and stoker therefor, with parts of the boiler or furnace being broken away and in section to show the coke tree preventing guard in operative position therein;

Figure 2 is a side elevation of a stoker fed boiler or furnace with parts thereof being broken away and in section to show the coke tree preventing guard being partially raised by means of the lifting bar;

Figure 3 is a view similar to that shown in Figure 2, but with the coke tree preventing guard supported in raised position and a poker in position to remove a clinker;

Figure 4 is an enlarged plan view of the improved coke tree preventing guard;

Figure 5 is a side elevation of the improved coke tree preventing guard with a portion thereof being broken away and in section, and

Figure 6 is a perspective view of the fulcrum supported pivoted guard plate lifting bar.

Like characters of reference are used throughout the following specification and the accompanying drawings to designate corresponding parts.

In carrying out the invention, there is shown a typical boiler or furnace generally designated by the reference numeral 1, the same having a fire box 2 in the bottom thereof lined with fire

brick 3. A grate 4 is provided at the bottom of the fire box 2, and a retort 5 is supported below and centrally thereof. A fire door 6 is provided for the boiler or furnace 1.

As seen from the drawings, both the fire brick 3 and grate 4 are supported upon the inwardly extending annular flange 1 formed integrally with the boiler or furnace 1.

A stoker including a hopper 8, feed tube 9, worm 10, and motor 11 for rotating the worm 10 is provided, and the feed tube 9 connects with the retort 5 in the usual manner.

The coke tree preventing guard which forms the subject matter of the instant invention comprises a cast plate 12 possessing weight, being formed of any desired fire resistant metal and of a shape to fit within either a round or rectangular boiler or furnace, resting upon the fire bed 13 within the fire box 2. The guard plate 12 is slightly bowed upwardly in cross section, and has a plurality of openings or apertures 14 formed through it to permit air to pass therethrough for complete combustion over the fire bed 13, and also to let the gases of combustion with the smoke and flame to pass upwardly therethrough.

One end of the guard plate 12 is provided with the spaced legs 15 which connect with and support the end bar 16 whose terminal ends are reduced as at 17 for receiving the loops 18 on the offset supporting legs 19 which are adapted to rest upon the upper surface of the fire bed 13. The opposite end of the guard plate 12 is formed with the end bar 20 extending in parallel relation to the end bar 16, and has one end reduced as at 21 for rotatably supporting the loop 22 on the end of the brace rod 23. The opposite or free end of the rod 23 is hooked as at 24 to better support the guard plate 12 when in elevated position. A cotter key 25 extends through the outer end 21 of the end bar 20 for retaining the looped end 22 of the brace rod 23 in position.

An integrally formed socket 26 is disposed on the upper surface of the guard plate 12 adjacent the end bar 20, and is adapted to receive the flattened end 27 of the guard plate lifting bar 28 when inserted into the boiler or furnace 1 through the opened fire door 6. The outer end of the bar 28 is looped as at 29 to provide a handle portion for grasping when using the lifting bar 28. An inverted T-shape fulcrum support 30 is provided, and is formed with the spaced bearing ears 31 between which the pivot pin 32 is supported, said pin 32 also passing through the bar 28 at a point nearer its inner end than to its outer end.

In operation, the guard plate 12 is disposed

upon the upper surface of the fire bed 13, and as the coal is fed upwardly through the fire bed by the stoker, it will be spread over the surface of the fire bed, being guided and directed by the arcuate under surface of the plate 12, thus preventing the building up and formation of coke trees which would otherwise form and cut down the efficiency of the boiler or furnace.

When clinkers have to be removed, the fire door 6 is opened, and the bar 28 is inserted into the boiler or furnace with its flattened end 27 engaged in the socket 26 on the guard plate 12, and with the fulcrum support 30 resting on the edge of the fire brick 3 of the fire box 2. Thus the looped handle 29 of the bar 28 is moved downwardly to raise the adjacent end of the guard plate 12 until the brace rod 23 is in vertical position, thus supporting the plate 12 with its forward end elevated, while a poker 33 is inserted within the furnace or boiler 1 to remove the clinker or clinkers. The bar 28 is then manipulated until the brace rod 23 again assumes a substantially horizontal position and the guard plate 12 once more rests upon the fire bed 13.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention, what I claim as new and desire to secure by Letters Patent of the United States is:

1. A coke tree preventing guard for boilers and furnaces comprising an apertured plate having end bars at its opposite ends, and supporting legs mounted on the ends of one of said end bars.

2. A coke tree preventing guard for boilers and furnaces comprising an apertured arcuate plate having end bars at the opposite ends thereof, supporting legs pivotally mounted on the ends of one of said bars, and means on said plate for lifting one end thereof.

3. A coke tree preventing guard for boilers and furnaces comprising an apertured arcuate plate having parallel bars formed at its opposite ends, offset supporting legs pivotally mounted on the ends of one of said bars, and means on said plate for lifting one end thereof.

4. A coke tree preventing guard for boilers and furnaces comprising an apertured arcuate plate having parallel bars formed at its opposite ends, offset supporting legs pivotally mounted on the ends of one of said bars, means on said plate for lifting one end thereof, and a bracing rod pivotally mounted on the opposite end of the plate from said supporting legs.

5. A coke tree preventing guard for boilers and furnaces comprising an arcuate weighted plate having a plurality of apertures formed therethrough, parallel extending bars on the opposite ends of said plate, one of said bars having reduced terminal bearing ends, offset supporting legs pivotally mounted on said terminal bearing ends, a lifting socket formed on the opposite end of said plate adjacent the other bar, said other bar having a terminal bearing end, and a hooked bracing rod pivotally mounted on the last named terminal bearing end of said other bar.

6. The subject matter as claimed in claim 5, and a cooperating pivotally mounted fulcrum supported plate lifting bar engageable with said lifting socket for lifting one end of said plate.

SANTO IMBRESCI.
